PILE-CUTTING MACHINE.

1,174,340.

Specification of Letters Patent.

Patented Mar. 7, 1916.

Application filed June 18, 1912. Serial No. 704,357.

To all whom it may concern:

Be it known that I, ARTHUR MORTON, of Warwick, in the county of Kent and State of Rhode Island, have invented certain new and useful Improvements in Pile-Cutting Machines; and I do hereby declare the following specification, taken in connection with the accompanying drawings, forming a part of the same, to be a full, clear, and exact description thereof.

In a pending application, Serial No. 387,960, I have shown and described an automatic pile cutting machine which is especially adapted for cutting velvets. In machines of this character it becomes necessary or desirable at times to run the fabric backward for a greater or less distance, and for this purpose the machine shown and described in said pending application is provided with means for reversing the machine and the travel of the fabric.

The present invention relates to improvements in the machine shown and described in said pending application and more particularly with respect to the matter of reversing the travel of the fabric when desired. In the machine of said pending application the backward or reverse travel of the fabric is effected by the reverse rotation of the drag-roll. With this construction it has been found in practice that more or less slack in the fabric is liable to be produced between the drag-roll and the driven roll located at the rear thereof, which is objectionable.

The primary feature of the present invention consists in providing means whereby the backward or reverse travel of the fabric will be effected by the reverse rotation of the driven roll which is located at the rear of the drag-roll, instead of by the reverse rotation of the drag-roll itself. In this connection a nip-roll is provided to coöperate with said driven roll. By this construction the liability of slack between the drag-roll and the driven roll referred to is obviated, and any slack in the fabric will be at the rear of said driven roll, where it is not objectionable.

In the machine of said pending application there is a spring-pressed nip-roll coöperating with the drag-roll and which serves to nip the fabric between said nip-roll and said drag-roll, and there is also a spring-pressed nip-roll coöperating with the feed-

roll and which serves to nip the fabric between said nip-roll and said feed-roll. Below the feed-roll there is a pair of supplemental feed-rolls, one of which is a driven roll and the other of which is a spring-pressed nip-roll, whereby the fabric is also nipped between said supplemental feed-rolls. With this construction the fabric, which hangs loose below the supplemental feed-rolls referred to and which therefore becomes more or less wrinkled or crinkled at that point, passes, when the travel of the fabric is reversed, between the several spring-pressed rolls referred to and their companion rolls in such wrinkled or crinkled condition, which has the effect to press or iron the wrinkles into the fabric, so to speak, and so that it is very difficult, if not impossible, to thereafter remove them.

A further feature of the invention consists in providing means whereby the several nip-rolls referred to may be moved away from their companion rolls and out of contact with the fabric when the travel of the fabric is reversed, and so that the fabric in traveling backward will simply drag over the companion rolls referred to, and so that the wrinkles in the fabric, instead of being pressed or ironed into the fabric, will be smoothed or ironed out by being thus dragged over these rolls and without being nipped at such points.

A further feature of the invention consists in providing a brake or drag for the feed-roll, with means for applying such brake or drag to said feed-roll when the travel of the fabric is reversed.

The invention further consists in certain combinations and arrangements of parts hereinafter described and claimed.

Referring to the drawings, Figure 1 is a side elevation of the forward end of the machine and showing the parts in the position which they occupy during the forward feed of the fabric. Fig. 2 is a similar side elevation of the forward end of the machine, but showing the parts in the position which they occupy during the backward or reverse travel of the fabric, and with a portion of one of the pulleys broken away. Fig. 3 is a longitudinal section through the front end of the machine, many of the parts being omitted for the purpose of showing the path of the traveling fabric with relation to the various rolls. Fig. 4 is a side elevation of

the forward end of the machine corresponding to Fig. 1, but taken from the opposite side of the machine. Fig. 5 is a section through the machine on the line $x-x$ of Fig. 1, looking toward the front of the machine. Figs. 6 and 7 are details.

The general construction and organization of the machine is the same as that shown in said pending application, and 19 inasmuch as the present improvements are all embodied in the forward end of the machine, it has been deemed necessary to show in the accompanying drawings only the forward end of the machine in which 15 the several features of improvement are thus embodied.

The machine comprises a suitable frame 1 in which the several operating parts are mounted. The fabric travels through the 20 machine in the form of an endless web. The fabric 3 after the race has been cut is carried down on to a traveling endless apron or lattice (not shown) at or near the bottom of the machine where it drops in folds, and 25 in this form is carried by the traveling apron to the rear of the machine. From the apron at the rear of the machine the fabric is carried up over a feed-roll and down an incline. At the foot of this incline 30 the fabric is carried upward over two fixed bars at the top of the frame. From the fixed bars at the top of the frame the fabric travels down another incline 8, around an idler roll 9, up over a belt driven roll 10, preferably rubber covered, down around another idler roll 11, then forward around a nip-roll 12, and around the drag-roll 13. After passing nearly around the entire periphery of the drag-roll 13 the fabric is 35 passed around the idler rolls 13^a, 13^b, arranged as shown in the drawings, and from the idler roll 13^b the fabric passes to the feed-roll 14. As will be seen, the roll 13^b serves to locate the fabric for presentation 40 to the knife, and also serves to support the fabric in proximity to the point of cutting, the knife (not shown) being located between said idler roll 13^b and the feed-roll 14, and with its cutting portion arranged to engage 45 the fabric at a point in proximity to said idler roll. From the feed-roll 14 the fabric passes around the nip-roll 15 and thence downward between a pair of supplemental feed-rolls 16, 17, the roll 16 being belt-driven and the roll 17 being movable toward 50 and from said roll 16 and acting as a nip-roll, and thence down on to the traveling apron above referred to.

The necessary tension at the cutting point 60 is produced by means of the rolls 13 and 14. The feed-roll 14 is positively driven, while the drag-roll 13 is provided with a friction device whereby a friction or drag may be put on said roll.

65 The main driving shaft 19 is provided

with a pulley 20 driven by a belt 21 leading from a motor or other source of power. On the opposite end of the driving shaft 19 is a pulley 22 from which a belt 23 extends to a pulley 24 on the left hand end of the feed-roll 14. On the driving shaft 19 adjacent to the main driving pulley 20 is a pulley 25 from which a cross belt 26 extends to a loose pulley 27 on the feed-roll 14. The pulley 27 is a two-step cone pulley, and from the smaller step of said pulley a belt 28 extends to a pulley 29 on the right hand end of the drag-roll 13.

On the left hand end of the drag-roll 13 are two pulleys 30 and 31, as shown in Fig. 80 2. From the pulley 30 a belt 32 extends around a pulley 33 on the left hand end of the supplemental feed-roll 16. From the pulley 31 a belt 34 extends to a pulley 35 on the left hand end of the roll 10. Thus, 85 as will be seen, both the supplemental feed-roll 16 and the roll 10 are driven rolls. On the right hand end of said roll 10 are two pulleys 36 and 37. From the pulley 36 a belt 38 extends to a pulley on the right hand 90 end of a feed-roll, which is located at the upper rear end of the machine. From the pulley 37 extends a belt 40 through which power is communicated for operating the traveling endless apron or lattice upon 95 which the fabric is carried in folds from the front to the rear of the machine.

The pulley 22 on the driving shaft 19 is loose on said shaft, but is adapted to be connected with said shaft by a suitable 100 clutch mechanism, preferably a friction clutch, as shown in the drawings. This clutch may be of any desired construction, and as it forms no part of the present invention, the detail construction of the clutch 105 shown need not be described. It will be understood that when the pulley 22 is connected with the driving shaft 19, the fabric will be fed through the machine, and when the pulley 22 is disconnected from the shaft 110 19, the feed of the fabric will be stopped. The clutch mechanism as a whole is designated as 47 in the drawings, and said clutch mechanism is adapted to be operated by the lever 48.

In machines of this character it is desirable that when the driving power is disconnected for the purpose of stopping the machine, the machine should be quickly brought to a full stop and so as to promptly 115 stop the feed of the fabric. For this purpose a brake mechanism is applied to some part of the feed mechanism to quickly stop the feed of the fabric whenever the driving power is disconnected.

In the arrangement shown the brake is applied to the drag-roll 13, or rather to the pulley 30 on said roll. This brake may be of any suitable construction, and in the drawings is shown as comprising a brake- 120 125 130

- shoe 49 which is adapted to be forced into contact with the inner surface of the flange of the pulley 30 by means of a coiled spring 50. The brake-shoe 49 is pivoted to one arm 5 of a supporting member 49^a held fast in the bearing of the drag-roll 13. Mounted in the other arm of said supporting member is a rock-shaft 49^b provided with an arm 49^c arranged to engage the free end of the brake-shoe 49, as shown in Fig. 1. An arm 49^d on said rock-shaft is pivotally connected to the upper end of a vertically movable bar 51. The brake-shoe 49 is normally, or while the machine is in operation, latched out of contact with the pulley-flange. The vertical bar 51 extends downward and is supported and guided by a bracket 52 extending from the frame of the machine. Adjustably secured to one side of this bar 51 is a block 53 adapted to engage or be engaged by the forward end of a movable bar 54. One end of the spring 50 is connected to said bar 51, the other end of said spring being connected to a bracket 55 on the frame. When the machine is running, the bar 51 is latched and held in its upper position, so as to hold the brake-shoe 49 out of contact with the flange of the pulley 30 by the end of the bar 54 engaging the block 53, as shown in Fig. 1. When, however, said movable bar 54 is moved rearward by any suitable means, as for example by an automatic stop motion, the bar 51 is thereby disengaged and is pulled downward by the spring 50, thereby rocking the rock-shaft 49^b and forcing the brake-shoe into contact with the flange of the pulley 30, stopping the feed of the fabric. In the machine shown means are to be provided for automatically throwing out the clutch 47 and for automatically applying the brake 49, but as these means form no part of the present invention, they are not shown in the drawings, and consequently will not be described.
- The means for releasing the brake in starting the machine to feed forward the fabric after the machine has been stopped and the brake applied will be next described. A foot-treadle 56 extends across the front of the machine, where it may be conveniently operated. This treadle is secured by means of arms 57, one on each side of the machine, to a rock-shaft 58, which extends across the machine and is arranged to turn in bearings on the frame. Connected to this rock-shaft are two weights 59, one on each side of the machine, which act to firmly hold the treadle 56 in its upper position. Formed integral with the arm 57 on the left hand side of the machine is an arm 60 to which is connected one end of a connecting rod 61, the other end of which rod is connected to one arm of a bell-crank lever 62 which is pivoted on the frame, as shown in Figs. 1 and 2. The other arm of this bell-crank lever is provided with a friction-roll 63 which underlies the lower end of the vertical bar 51 which is connected to the brake-shoe. When the bell-crank lever 62 is rocked by depressing the treadle 56, one result will be to lift the brake-shoe 49 out of contact with the flange of the pulley 30 and thus release the brake.
- Connected to the arm of the bell-crank lever 62, to which the rod 61 is connected, is another connecting rod 64, the opposite end of which is connected to an arm 65 secured to a rock-shaft 66 mounted in bearings secured to the frame of the machine. In the present machine the reversing clutch to be hereinafter referred to is also operated by a foot-treadle 56, and for this reason the connection between the arm 65 and the clutch-lever 48, instead of being a permanent connection, is made detachable, but when the connection between said members 65 and 48 is made and the treadle 56 is depressed, the further result will be that the arm 65 will be rocked and in its turn will serve to pull inward the lower end of the clutch lever 48, and thus throw in the clutch 47 and connect the pulley 22 to the driving shaft 19.
- Pivoted to the clutch-lever 48 is a latch-bar 68 provided with a shoulder 69 adapted to engage the bracket 70, through a slot in which bracket the end of the latch-bar 68 extends. When the clutch 47 is thrown in to connect the pulley 22 with the shaft 19, the upper end of the clutch-lever 48 is moved away from the bracket 70, and so as to draw the latch-bar 68 outward and into a position where the shoulder 69 on said latch-bar will engage said bracket, and thereby latch and hold the clutch in its engaged position, the parts then being in the position shown in Fig. 5. The weight of the latch-bar 68 will ordinarily be sufficient to cause said bar to fall down and engage the latch. If desired, however, a spring may be employed for this purpose. Preferably also a spring 48^a is connected to the upper end of the clutch-lever 48 to automatically throw out the clutch when the latch 68 is disengaged.
- It is desirable in machines of this character to provide means to reverse the machine and the travel of the fabric, in order that if the knife should fly out of the race, or any other accident happen, the fabric may be run back a short distance for the purpose of reinserting the knife in the race. This reversal of the machine is effected by means of the cross-belt 26 running on one of the steps of the cone-pulley 27 on the feed-roll 14. This cross-belt 26 is driven by the pulley 25 which is loose on the main driving shaft, but which is provided with a clutch 71 adapted to be operated by a lever 72 for clutching said pulley to said driving shaft. Preferably a spring 72^a is connected to the lower end of the clutch-lever 72 acting in a direction to throw out the clutch 71, and an

adjustable stop 72^b is provided to limit the movement of said clutch-lever under the action of said spring. In the present machine, as hereinbefore stated, this reversing clutch 5 71, as well as the forward feed-clutch 47, is operated by a foot-treadle 56, said reversing clutch, like the main starting clutch, being operated from the rock-shaft 66, means being provided for determining which of 10 these two clutches will be operated when the foot-treadle is depressed.

Mounted on the rock-shaft is a sliding collar 73 having an arm 74 projecting rearwardly therefrom, which arm carries a vertical rod 75, which rod partakes of the sliding movements of said collar 73. Secured to the rock-shaft 66 are two rearwardly extending arms 76 and 77, which serve as guides for the rod 75 as it is moved upward or downward by said sliding collar. The sliding movements of the collar 73 and the rod 75 are effected by means of a hand-lever 78 pivoted to the frame at the front of the machine. A bell-crank lever 79 is pivoted 25 to the frame, the horizontal arm of which lever is provided with a projecting pin 80 adapted to enter a groove in the sliding collar 73. The vertical arm of said bell-crank lever 79 is connected with the hand-lever 78 by connections which will be hereinafter described.

Connected to the lower end of the clutch-lever 48 is a latch-bar 82, the free end of which latch-bar is supported by a pin 83 projecting from the frame, which pin extends through a slot in said latch-bar, as shown in Fig. 5. Said latch-bar 82 is provided with a shoulder 82^a adapted to be engaged by the upper end of the sliding rod 75. To the lower end of the reversing clutch lever 72 is connected a latch bar 84 which extends across the machine, said latch-bar being likewise provided with a suitable shoulder 84^a adapted to be engaged by the lower end of said sliding rod 75. In order to provide for the swinging movement imparted to the sliding rod 75 by the rocking of the shaft 66 it is desirable to provide a swivel connection between the arm 77 and the latch-bar 84. Loosely mounted in the end of the arm 77 is a hollow stud 85, the lower end of which is forked to receive the end of the latch-bar 84, said latch-bar being connected to the forked end of said stud by means of a cross-pin 85^a. The hollow stud is held in place by means of a nut 86 which engages the upper end of said stud. As will be understood, the lower end of the sliding rod 75 projects through said hollow stud, and so that the lower end of said rod may be moved into engagement with the shoulder 84^a on the latch-bar 84.

With the construction above described the operation of starting or reversing the machine is as follows: When the hand-lever 78

is thrown backward into the position shown in Fig. 1 the sliding collar 73 and the sliding rod 75 will be moved upward so as to bring the upper end of said rod into engagement with the shoulder on the latch-bar 82. With the sliding rod held in this position the foot-treadle is depressed, which will serve to turn the rock-shaft 66, thereby giving a swinging movement to the rod 75, which movement will serve to actuate the latch-bar 75 and the clutch 48 to throw the clutch 47 into engagement. When now it is desired to reverse the machine, the hand-lever 78 is pulled forward into the position shown in Fig. 2, which will serve to move the sliding collar and the sliding rod downward, and so as to move the upper end of said rod out of engagement with the latch-bar 82 and to move the lower end of said rod into engagement with the latch-bar 84. By now depressing the foot-treadle and thereby turning the rock-shaft 66, a swinging movement will be given to the sliding rod 75 which will serve to move the latch-bar 84 and the lever 72 to throw in the reversing clutch 71.

As will be understood, when the machine is at rest both the clutch 47 and the reversing clutch 71 are out of engagement. Ordinarily at this time the sliding rod 75 will be in its proper position and in engagement with the latch-bar 82, and so that by the depression of the foot-treadle the feed-clutch 47 will be thrown into engagement so as to thereby start the forward feed of the machine. In order to permit the necessary swinging movement of the rock-shaft 66 to operate the latch-bar 82, without at the same time operating the latch-bar 84 said latch-bar 84 is provided with an elongated slot 84^b through which the cross-pin 85^a passes, as shown in Fig. 5.

Referring now to the connections between the bell-crank lever 79 and the hand-lever 78 for shifting the position of the sliding collar 73 and the sliding rod 75, the lever 78 is provided with a projecting arm 86 to which is pivoted one end of a connecting rod 87. The other end of said connecting rod is pivoted to the arm 88 of a bell-crank lever pivoted on a bracket 89. To the other arm 90 of said bell-crank lever is pivoted one end of a connecting rod 91, the other end of which rod is connecting to the arm 92 of a bell-crank lever pivoted to the bracket 93. To the other arm 94 of said bell-crank lever is connected one end of a connecting rod 95, the other end of which is connected to the arm of the bell-crank lever 79. With the above construction, when the hand-lever is thrown forward into the position shown in Fig. 1, the sliding rod 75 will be moved upward and when the lever 78 is pulled backward into the position shown in Fig. 2 the sliding rod 75 will be moved downward.

As above stated, the supplemental feed-roll 10 is a belt driven roll, and in the present construction the backward or reverse travel of the fabric is effected by the reverse rotation of said driven roll 10. For this purpose a nip-roll 96 is provided, which said nip-roll is adapted to be moved toward or from said roll 10. During the forward feed of the fabric said nip-roll 96 is held away from the roll 10 and out of contact with the fabric passing over said roll, but when the fabric is to be caused to travel backward, said nip-roll is moved toward the roll 10 and into contact with the fabric thereon and so as to nip the fabric between said rolls, whereby the necessary backward pull upon the fabric will be produced when the roll 10 is rotated in the reverse direction. The position of said nip-roll 96 is controlled by the hand-lever 78 in the following manner:

Referring to Fig. 5, the nip-roll 96 is pivoted in the lower ends of two arms 97, 97, one at each side of the machine, which said arms are loosely pivoted on a rock-shaft 98 which extends across the machine. A torsion-spring 99 has one end connected to the hub of the arm 97 and the other end connected to a collar 100 mounted on the rock-shaft 98. A suitable amount of tension is set up in the spring 99 by turning the collar 100 on the shaft 98, said collar being held in adjusted position by a set screw 101. The springs 99 act in a direction to move the nip-roll 96 toward the roll 10.

To the arm 90 of the bell-crank lever above referred to is connected one end of a connecting rod 102, the other end of which rod is connected to the end of an arm 103 secured to the rock-shaft 98. Secured to said rock-shaft are two downwardly extending arms 104. From the lower end of each of these arms projects inwardly a pin 105, which pin extends in front of the lower end of the arm 97.

While the machine is running forward and the fabric being fed to the knife, and with the hand-lever in the position shown in Fig. 1, the binding roll 96 is held against the action of the springs 99 away from the roll 10 and out of contact with the fabric. When now the machine is to be run in the reverse direction to cause the fabric to travel backward the pulling of the hand-lever 78 forward into the position shown in Fig. 2 serves, through the connections above described to rock the shaft 98 in a direction to move the pins 105 away from the arms 97, thereby permitting the springs 99 to move the nip-roll 96 toward the roll 10 and into contact with the fabric and thereby nip the fabric between said rolls, said roll 96 being held in this position during the backward travel of the fabric by the action of said springs. When the fabric is to be

again fed forward the hand-lever 78 is thrown back into the position shown in Fig. 1, and this movement of the hand-lever through the connections serves to rock the rock-shaft 98 in the opposite direction and thereby, through the engagement of the pins 105 with the arms 97, to move the binding roll 96 away from the roll 10 and out of contact with the fabric.

During the forward feed of the fabric the fabric is nipped at the drag-roll 13 by the spring-pressed nip-roll 12 which is mounted in the ends of arms 106 pivoted to the frame, one at each side of the machine, which arms are acted upon by springs 107. The fabric is also nipped at the feed-roll 14 by the spring-pressed nip-roll 15 which is mounted in the ends of arms 108 pivoted on the frame, one at each side of the machine, which arms are acted upon by springs 109. The fabric is also nipped between the supplemental feed-roll 16 and the spring-pressed nip-roll 17 which cooperates therewith. Said roll 17 is mounted in arms 110, one at each side of the machine, said arms being secured to a rock-shaft 111. Adjustably secured to said rock-shaft 107 are two arms 112, one at each side of the machine. To each of said arms 112 is connected one end of a spring 113, the other end of which is connected to a bracket 114 secured to the frame, as shown in Fig. 1. The action of the springs 113 serve to move the nip-roll 17 toward the roll 16 and to hold said roll 17 in contact with the fabric, so as to nip the same between said rolls.

When the fabric is to be caused to travel backward it is desirable that the nip-rolls 12, 15, and 17 should be moved away from their companion rolls, and so as to release the fabric at those points. The position of said nip-rolls 12, 15, and 17 is likewise controlled by the hand-lever 78 in the following manner:

Secured to the rock-shaft of the hand-lever 78 are two arms 115, one at each side of the machine, which said arms underlie the levers 108, as shown in Fig. 1. Extending across the machine and overlying the levers 108 is a cross-bar 116. Each end of this cross-bar is connected by a screw 117 with the end of the corresponding lever 106, as shown in Fig. 1. With this construction the operation is as follows: While the fabric is being fed forward the nip-rolls 12 and 15 are held in position to nip the fabric by the springs 107 and 109. When now the travel of the fabric is to be reversed and the lever 78 is pulled forward into the position shown in Fig. 2, the arms 115 engaging the levers 108 serve to raise the rear ends of said levers, thereby moving the nip-roll 15 away from the feed-roll 14. The upward movement of said levers 108 serves to raise the cross-bar 116 and the forward ends of the levers 106, thereby moving the nip-roll 12

away from the drag-roll 13, and so that the fabric will thus be released at both the feed-roll and the drag-roll.

The means for moving the nip-roll 17 away from its companion roll 16 are as follows: Extending from the rock-shaft of the hand-lever 78 are two arms 118, one at each side of the machine. Pivoted connected to said arm 118 is a link 119 which is provided 10 with an elongated slot 120. Passing through said slot 120 is a pin 121 secured to the lever 112. When the hand-lever 78 is pulled back to the position shewn in Fig. 2 the link 119 is raised until the lower end of the slot is 15 brought into engagement with the pin 121, when the further movement of the hand-lever serves to raise the lever 112, thereby rocking the rock-shaft 111 in a direction to move the nip-roll 17 away from the roll 16, and thus release the fabric at this point also.

When the fabric is caused to travel backward it is desirable to provide a brake or drag for the feed-roll 14, and in the present construction such a brake or drag is provided with means for controlling the same by the movements of the hand-lever 78. The brake 122 is pivoted to the frame at 123 and is curved to underlie the feed-roll 14, as shown in Fig. 1. The movement of said 25 brake into and out of engaging position is effected by a pair of toggle-levers 124, 125, the lever 124 being pivotally connected to the free end of the brake 122 and the lever 125 being pivotally connected to the frame. 30 A connecting rod 126 connects the lever 124 with the arm 86 of the hand-lever 78.

The operation of these parts is as follows: When the fabric is being fed forward and the lever 78 is in the position shown in Fig. 40 1, the toggle levers 124 and 125 are broken and the brake 122 is out of engagement with the feed-roll 14. When now the fabric is to be caused to travel backward and the lever 78 is pulled forward into the position shown in Fig. 2, the movement of said lever through the connections referred to serves to straighten the toggle levers and thereby force the brake 122 upward and into engagement with the feed-roll.

50 The operation of the several parts has been already sufficiently described, and it will not be necessary to repeat such description. It will be seen that when the machine is to be run in the reverse direction 55 and the fabric thus caused to travel backward, the proper manipulation of all the parts for this purpose is effected solely by the movement of the hand-lever 78, and that when said hand-lever has been so moved all that remains to be done is simply to depress the foot-treadle 56, thereby throwing in the reversing clutch 71. Thus when the hand-lever 78 is moved from the position shown in Fig. 1 to the position shown in Fig. 2, 60 the following operations are simultaneously

performed, viz., the sliding rod 75 is moved into proper position to engage the latch-bar 84 connected to the reversing clutch-lever 72, so that when the foot-treadle is depressed the reversing clutch will be thrown in; the companion roll 96 is caused to move toward the roll 10 and to nip the fabric between said rolls; the binding rolls 12, 15, and 17 are each moved away from their companion rolls and the fabric released at each of said points; and finally the brake is applied to the feed-roll. Thus when the machine is reversed for the backward travel of the fabric, the movement of the hand-lever referred to serves to release 80 the fabric at the several points where it was nipped during the forward feed, and also serves to nip the fabric at the driven roll located at the rear of the drag-roll, and so that the backward travel of the fabric will be caused by the reverse rotation of said driven roll. As said driven roll is located at the rear of the drag-roll there is no liability of any slack between said rolls during the backward travel of the fabric. It will 85 be further seen that as the nip of the fabric is released at the feed-roll and at the supplemental feed-rolls located below the same, any wrinkles which may form in the fabric as it hangs loose below said feed-rolls, instead of being ironed or pressed into the fabric, will be smoothed or ironed out of the fabric as the same is dragged over the rolls about which it passes.

What I claim as my invention and desire 100 to secure by Letters Patent is:

1. A pile cutting machine having in combination a feed-roll, a drag-roll, a driven roll at the rear of said drag-roll, and means for rotating said driven roll in the reverse 105 direction to effect the backward travel of the fabric.

2. A pile cutting machine having in combination a feed-roll, a drag-roll, a driven roll at the rear of said drag-roll, and a nip-roll adapted to coöperate with said driven roll.

3. A pile cutting machine having in combination a feed-roll, a drag-roll, a driven roll at the rear of said drag-roll, means for 115 rotating said driven roll in the reverse direction, and a nip-roll adapted to coöperate with said driven roll.

4. A pile cutting machine having in combination a feed-roll, a drag-roll, a driven 120 roll at the rear of said drag-roll, a nip-roll, and means for moving said nip-roll toward and from said driven roll.

5. A pile cutting machine having in combination a feed-roll, a drag-roll, a driven 125 roll at the rear of said drag-roll, a nip-roll, a spring for moving said nip-roll toward said driving roll, and means for moving said nip-roll away from said driven roll against the action of said spring.

6. A pile cutting machine having in combination a feed-roll, a drag-roll, a driven roll at the rear of said drag-roll, means for rotating said driven roll in opposite directions, a nip-roll, means for moving said nip-roll away from said driven roll when said driven roll is to be rotated in the forward direction, and means for moving said nip-roll toward said driven roll when said driven roll is to be rotated in the reverse direction. 70
7. A pile cutting machine having in combination a feed-roll, a drag-roll, a nip-roll adapted to coöperate with said drag-roll, and means for moving said nip-roll toward and from said drag-roll. 75
8. A pile cutting machine having in combination a feed-roll, a drag-roll, a nip-roll adapted to coöperate with said feed-roll, and means for moving said nip-roll toward and from said feed-roll. 80
9. A pile cutting machine having in combination a feed-roll, a drag-roll, a pair of supplemental feed-rolls, and means for releasing and nipping the fabric by opening and closing said supplemental feed-rolls. 85
10. A pile cutting machine having in combination, a feed-roll, a drag-roll, a nip-roll adapted to coöperate with said drag-roll, and means for moving said nip-roll away from said drag-roll for the backward travel of the fabric. 90
11. A pile cutting machine having in combination a feed-roll, a drag-roll, a nip-roll adapted to coöperate with said feed-roll, and means for moving said nip-roll away from said feed-roll for the backward travel of the fabric. 95
12. A pile cutting machine having in combination a feed-roll, a drag-roll, a pair of supplemental feed-rolls, and means for separating said supplemental feed-rolls to release the fabric for the backward travel of the fabric. 100
13. A pile cutting machine having in combination a feed-roll, a drag-roll, means for nipping the fabric at said drag-roll for the forward feed of the fabric, and means for releasing such nip for the backward travel of the fabric. 105
14. A pile cutting machine having in combination a feed-roll, a drag-roll, means for nipping the fabric at said feed-roll for the forward feed of the fabric, and means for releasing such nip for the backward travel of the fabric. 110
15. A pile cutting machine having in combination a feed-roll, a drag-roll, means for nipping the fabric both at said drag-roll and at said feed-roll for the forward feed of the fabric, and means for releasing both of such nips for the backward travel of the fabric. 115
16. A pile cutting machine having in combination a feed-roll, a drag-roll, a driven roll at the rear of said drag-roll, and means for nipping the fabric at said driven roll for the backward travel of the fabric and releasing such nip for the forward feed of the fabric. 120
17. A pile cutting machine having in combination a feed-roll, a drag-roll, means for nipping the fabric at said drag-roll for the forward feed of the fabric and releasing such nip for the backward travel of the fabric, a driven roll at the rear of said drag-roll, and means for nipping the fabric at said driven roll for the backward travel of the fabric and releasing such nip for the forward feed of the fabric. 125
18. A pile cutting machine having in combination a feed-roll, a drag-roll, a driven roll at the rear of said drag-roll, means for rotating said rolls in one direction or the other, means for nipping the fabric at said driven roll when said rolls are rotated in the reverse direction, and means for releasing such nip when said rolls are rotated in the forward direction. 130
19. A pile cutting machine having in combination a feed-roll, a drag-roll, a driven roll at the rear of said drag-roll, means for rotating said rolls in one direction or the other, a nip-roll adapted to be moved toward and from said driven roll, and means for controlling the direction of rotation of said rolls and the movements of said nip-roll toward and from said driven roll. 135
20. A pile cutting machine having in combination a feed-roll, a drag-roll, a driven roll at the rear of said drag-roll, means for rotating said rolls in one direction or the other, nip-rolls adapted to be moved toward and from said drag-roll and said driven roll, respectively, and means for controlling the direction of rotation of said rolls and the movements of said nip-rolls toward and from their companion rolls. 140
21. A pile cutting machine having in combination a feed-roll, a drag-roll, a driven roll at the rear of said drag-roll, means for rotating said rolls in one direction or the other, nip-rolls adapted to be moved toward and from said drag-roll, said feed-roll and said driven roll, respectively, and means for controlling the direction of rotation of said rolls and the movements of said nip-rolls toward and from their companion rolls. 145
22. A pile cutting machine having in combination a feed-roll, a drag-roll, a driven roll at the rear of said drag-roll, a nip-roll adapted to be moved toward and from said driven roll, a pair of supplemental feed-rolls, and means for moving said nip-roll toward and from said driven roll and for moving one of said supplemental feed-rolls toward and from the other. 150
23. A pile cutting machine having in com- 155

bination a feed-roll, a drag-roll, a driven roll at the rear of said drag-roll, means for rotating said rolls in one direction or the other, a nip-roll adapted to be moved toward and from said driven roll, a pair of supplemental feed-rolls, one of which constitutes a nip-roll, and means for controlling the direction of rotation of said rolls and the movements of said nip-rolls toward and from their companion rolls.

24. A pile cutting machine having in combination a feed-roll, a drag-roll, a driven roll at the rear of said drag-roll, a nip-roll adapted to coöperate with said driven roll, a lever, and connections from said lever to said nip-roll for controlling the position thereof with respect to said driven roll.

25. A pile cutting machine having in combination a feed-roll, a drag-roll, a driven roll at the rear of said drag-roll, nip-rolls adapted to coöperate with said drag-roll and said driven roll, a lever, and connections from said lever to said nip-rolls for controlling the position thereof with respect to their companion rolls.

26. A pile cutting machine having in combination a feed-roll, a drag-roll, a driven roll at the rear of said drag-roll, nip-rolls adapted to coöperate one with each of said rolls, a lever, and connections from said lever to each of said nip-rolls for controlling the position thereof with respect to their companion rolls.

27. A pile cutting machine having in combination a feed-roll, a drag-roll, a driven roll at the rear of said drag-roll, a nip-roll adapted to coöperate with said driven roll, a brake for said feed-roll, a lever, and connections from said lever to said nip-roll and said brake.

28. A pile cutting machine having in combination a feed-roll, a drag-roll, a driven roll at the rear of said drag-roll, nip-rolls

adapted to coöperate one with each of said rolls, clutches for controlling the rotation of said rolls in opposite directions, a lever and connections from said lever to said nip-rolls and said clutches.

29. A pile cutting machine having in combination a feed-roll, a drag-roll, a driven roll at the rear of said drag-roll, nip-rolls adapted to coöperate one with each of said rolls, clutches for controlling the rotation of said rolls in opposite directions, a brake for said feed-roll, a lever, and connections from said lever to said nip-rolls, said clutches, and said brake.

30. A pile cutting machine having in combination two driven rolls, one to travel the fabric in a forward direction, the other to travel the fabric in a reverse direction, and nip-rolls adapted to coöperate one with each of said driven rolls.

31. A pile cutting machine having in combination two driven rolls adapted to be rotated in opposite directions, nip-rolls adapted to coöperate one with each of said driven rolls, and means whereby one of said nip-rolls may be moved into coöoperative relation with its companion driven roll, and the other nip-roll moved out of coöoperative relation with its companion nip-roll.

32. A pile cutting machine having in combination two driven rolls adapted to be rotated in opposite directions, nip-rolls adapted to coöperate one with each of said driven rolls, and means whereby one of said nip-rolls may be moved into coöoperative relation with its companion roll, or both of said nip-rolls may be moved out of coöoperative relation with said driven rolls.
